UNITED STATES PATENT OFFICE.

JOHN FRANCIS O'MALLEY, OF MOUNT VERNON, NEW YORK.

MACHINE-GUN.

1,329,922.

Specification of Letters Patent.

Patented Feb. 3, 1920.

Application filed December 11, 1918. Serial No. 266,194.

To all whom it may concern:

Be it known that I, JOHN FRANCIS O'MALLEY, a subject of the King of Great Britain, having declared my intention to 5 become a citizen of the United States, and a resident of Mount Vernon, in the county of Westchester and State of New York, have invented a new and Improved Machine-Gun, of which the following is a full, 10 clear, and exact description.

The invention relates to machine guns such as shown and described in the application for Letters Patent of the United States, Serial No. 181,024, filed by me on 15 July 17, 1917.

The object of the present invention is to provide a new and improved machine gun arranged to permit the use of interchangeable gun barrels, of which one is water 20 cooled, another is double, reversible and air cooled, and the third is a single air cooled barrel. Another object is to provide a perfect balance in the rotating cartridge wheel 25 and to permit operating the crank shaft from one side of the gun instead of from underneath, as disclosed in my previous application above referred to.

With these and other objects in view, the invention consists of certain novel features 30 of construction, as hereinafter shown and described and then specifically pointed out in the claims.

A practical embodiment of the invention is represented in the accompanying drawings forming a part of this specification, in 35 which similar characters of reference indicate corresponding parts in all the views.

Figure 1 is a side elevation of the machine gun provided with a water cooled barrel;

40 Fig. 2 is a plan view of the same;

Fig. 3 is an enlarged cross section of the same on the line 3-3 of Fig. 5;

Fig. 4 is a similar view of the same on the line 4-4 of Fig. 5;

45 Fig. 5 is an enlarged longitudinal central section of the machine gun;

Fig. 6 is a side elevation of the machine gun provided with reversible and water cooled barrels;

50 Fig. 7 is a similar view of the machine gun provided with a single air-cooled barrel; and

Fig. 8 is a side elevation of one of the barrels shown in Fig. 6.

55 The gun body or main frame 10 of the machine gun is preferably made in two parts

11 and 12 fastened together by transverse screws 13, and the said parts 11 and 12 are provided with transversely extending interlocking tongues and grooves, one fitting into 60 the other to securely hold the parts against longitudinal movement one on the other, as will be readily understood by reference to Fig. 2. The forward end of the part 12 of the gun body 10 is provided with a recess 65 20 and with a forwardly extending spindle 21 adapted to support either a single water jacketed barrel 22 or two reversible barrels 23, 24 (see Fig. 6) provided with transversely extending air cooled ribs 25, 26 for 70 keeping the barrels cooled by the action of the surrounding air. The barrel 23 may be separately mounted on the spindle 21, as shown in Fig. 7. The barrel 22 is provided with bearings 30 and 31, of which the rear 75 bearing 30 and the rear end 32 of the barrel fit into the recess 20, and the said bearings 30 and 31 engage the spindle 21. A screw 33 screws into the part 11 of the gun body 10 against the bearing 30 to securely hold 80 the barrel 22 in position on the gun body. The forward end of the spindle 21 is provided with a nut 34 and a spring 35 is coiled on the spindle and interposed between the said nut 34 and the bearing 31. The 85 nut 34 and the spring 35 can be readily removed whenever it is desired to interchange the barrel 22 with the other barrels 23, 24. The barrel 23 is provided with spaced bearings 40, 41, and a bearing 42 is formed on 90 the barrel 24 and fits between the bearings 40 and 41. The rear end of the bearing 40 is adapted to pass into the recess 20 the same as the bearing 30 and is adapted to be fastened therein by the set screw 33. The bearings 40, 41 and 42 engage the spindle 21 and the spring 35 is in this case interposed between the bearing 41 and the nut 34, as plainly shown in Fig. 6 and 7. By reference to Fig. 7 it will be noticed that the barrel 95 24 can be omitted but when in conjunction with the barrel 23 its rear end fits into the recess 20, and when it is desired to reverse the barrels 23 and 24, that is, to move the barrel 23 out of operative position relative to the gun body and to move the barrel 24 into operative position relative to the said gun body, then it is only necessary for the operator to slide the two barrels 23 and 24 outwardly until the inner ends of the barrels 105 disengage the recess 20 to allow the operator to turn the barrels on the spindle 110

21 until the barrel 24 is uppermost and the barrel 23 is lowermost. On the operator now releasing the barrels, the spring 35 causes the rear ends of the barrels to reengage the recess 20. The barrels are next fastened in place by screwing up the set screw 33, which is temporarily unscrewed during the reversing operation as above mentioned.

10 The gun body 10 is provided with a cartridge wheel chamber 50 having openings 51 at the sides for the passage in a transverse direction of the cartridge belt 52 carrying the cartridges 53 adapted to move successively into firing position relative to the bore 15 54 formed in the gun body 10 and in register with the bore of the barrel 22, 23 or 24 in use at the time, as above explained. The cartridge belt 52 and the cartridges 53 engage a cartridge wheel 60 arranged within 20 the chamber 50 and provided with a shaft 61 journaled in suitable bearings formed in the gun body 10. On the shaft 61 is secured a gear wheel 62 in mesh with a gear wheel 63 secured on a longitudinally extending shaft 25 64 journaled in the gun body 10, as plainly indicated in Fig. 5. The rear end of the shaft 64 passes out of the gun body and passes along the under side thereof and on this rear end is secured a bevel gear wheel 65 30 in mesh with a bevel gear wheel 66 secured on a transversely extending shaft 67 journaled in suitable bearings 68 attached to the under side of the gun body 10, as plainly shown in Fig. 3. A crank arm 69 is attached 35 to the right hand side of the shaft 67 to permit the user of the gun to conveniently turn the shaft 67 with a view to rotate the shaft 64 which by the gear wheels 63, 62 rotates the shaft 61 and consequently the cartridge 40 wheel 60 to feed the cartridge belt 52 through the chamber 50 for the purpose above described.

45 In order to fire the cartridges 53 as they successively move into operative position in the gun body 10, use is made of a firing pin 70 sliding in the gun body and attached to the forward end of a hammer 71 pressed in a forward direction by a spring 72, as plainly shown in Fig. 5. The hammer 71 is 50 provided at its forward end with a tooth 73 engaged successively by teeth 74 of a cam wheel 75 rotating with the cartridge wheel 60. Thus when the cartridge wheel is turned, the cam wheel 75 pushes the hammer 55 71 rearwardly against the tension of the spring 72, and then the cam wheel releases the hammer 71 and allows the same to move forward by the action of its spring 72 to fire the cartridges 53 moved into operative position 60 during the turning of the cartridge wheel 60. This mechanism is practically the same as the one described in the application above referred to so that further detailed description of the same is not deemed 65 necessary. The forward end of the gun

body 10 is attached to the rear end 80 of a lever 81 by the use of a transverse pin 82 (see Figs. 1 and 4), and the said lever 81 is pivoted at 82 on a post 83 having a depending pivot 84 journaled in a support 85 preferably in the form of a tripod having legs 86. The rear end of the lever 81 is pivotally connected with a screw rod 90 on which screws a nut 91 mounted to turn in a bearing 92 forming part of the post 83. By turning 75 the nut 91, the screw rod 90 is moved up or down according to the direction in which the nut is turned, and this movement given to the screw rod 90 causes an up or down swinging movement of the lever 81 to elevate or depress the gun body and with it the barrel mounted thereon. It will be noticed that by the arrangement described the gun body and its barrel can be minutely adjusted to insure accurate shooting and the 80 gun body and its barrel may be readily swung to one side or the other according to the direction in which the shot is to be fired.

The gun body 10 and the barrels are provided with suitable rear and front sights 100 90 and 101 of any approved construction.

Having thus described my invention, I claim as new and desire to secure by Letters Patent:—

1. In a machine gun, a gun body provided 95 at its forward end with a recess, a spindle extending forwardly from the said recessed end of the gun body, and a plurality of barrels arranged for interchangeable engagement with the said spindle and the said recess to hold the gun barrel in operative relation to the gun body, the said barrels having means for cooling the same, one of the said barrels having means for cooling it by air and another of the said barrels being provided with a water jacket for the circulation of water to cool the barrel. 100 105

2. In a machine gun, a gun body provided at its forward end with a recess and with a forwardly extending spindle, a barrel having spaced bearings engaging the said spindle, and a second barrel having a bearing fitting between the said spaced bearings and engaging the said spindle, the rear ends of the said barrels engaging the said recess. 110 115

3. In a machine gun, a gun body provided at its forward end with a recess and with a forwardly extending spindle, a barrel having spaced bearings engaging the said spindle, a barrel having a bearing fitting between the said spaced bearings and engaging the said spindle, the rear ends of the said barrels engaging the said recess, a cap on the forward end of the said spindle, and a spring coiled on the said spindle and arranged 120 intermediate the said cap and the forward one of the said bearings. 125

4. In a machine gun, a gun body provided at its forward end with a recess and with a forwardly extending spindle, a barrel hav- 130

ing spaced bearings engaging the said spindle, a second barrel having a bearing fitting between the said spaced bearings and engaging the said spindle, the rear ends of the 5 said barrels engaging the said recess, a cap on the forward end of the said spindle, a spring coiled on the said spindle and arranged intermediate the said cap and the forward one of the said spaced bearings, and a fastening means on the said gun body and 10 engaging the rear one of the said bearings to fasten the gun barrels in place.
